UNITED STATES PATENT OFFICE.

RICHARD C. ROSE, OF OSCEOLA, ARKANSAS.

WATCHMAN'S CLOCK.

971,310.

Specification of Letters Patent. Patented Sept. 27, 1910.

Application filed March 10, 1910. Serial No. 548,356.

To all whom it may concern:

Be it known that I, RICHARD C. ROSE, a citizen of the United States, residing at Osceola, in the county of Mississippi and 5 State of Arkansas, have invented a new and useful Watchman's Clock, (Case B,) of which the following is a specification.

This invention has reference to improvements in watchmen's clocks and its object 10 is to provide means co-acting with the clock whereby the clock will automatically set itself into condition to cause an alarm if the watchman fails to properly operate means at a predetermined station or stations at a 15 predetermined time.

The invention will be best understood from a consideration of the following detail description taken in connection with the accompanying drawings forming a part of 20 this specification, in which drawings the figure is a diagram illustrating a watchman's clock with the invention applied.

Referring to the drawings there is shown a clock 1 which may be of any approved 25 type and need not differ from ordinary clocks so far as the time side of the clock is concerned. The clock is provided with a hand or arm 2 driven by the time movement or otherwise driven in timed relation to the 30 time movement and this hand or arm is designed to form part of an electric circuit and is therefore made of conducting material either wholly or in part. In the path of the arm 2 are contact fingers 3, one or more 35 in number, and each contact finger 3 is constantly in the path of the hand or arm 2 so as to be electrically engaged thereby at predetermined times, preferably once in each complete movement of rotation of the 40 hand or arm 2 about its axis. Each finger 3 may be a light spring finger, or a spring brush may be carried by the hand or arm 2, but however the electric contact is brought about the structure is such that the accuracy 45 of the time movement of the clock is not sensibly affected, while at the same time ample provision is made for good electrical connection at these points. The hand 2 may be one of the time indicating hands of the 50 clock or may be a separate arm hidden from vision if such be desirable.

At an appropriate point there is mounted an armature lever 4 and if desirable any appropriate number of armature levers 4 may 55 be distributed about the clock so that a contact brush 5 on each armature lever 4 may be

moved into and out of the path of the hand or arm 2 under conditions to be hereinafter described. In the path of the lever 4 is a stop pin 6 arresting the movement of the 60 lever in one direction when the contact finger 5 is in the path of the hand 2. The movement of the armature lever 4 toward the pin 6 is caused by a spring 7, or where conditions permit may be caused by gravity. 65 The armature lever 4 has its free end in the path of a latch arm or lever 8 provided with a hook or latch end 9 adapted to underride the free end of the lever 4 when the latter is moved in a direction to carry the finger 5 70 out of the path of the hand 2. The lever 8 is urged in a direction to engage the armature lever 4 by a spring 10 or otherwise and a stop pin 11 may determine the movement of the lever 8 under the action of the 75 spring 10.

The lever 4 carries an armature 12 controlled by an electromagnet 13 which in turn is included in a circuit made up of conductors 14, 15 leading to a distant point constituting a watchman's station. One of these conductors, say the conductor 14 includes a circuit controlling device 16 shown in the drawings as a simple circuit closing means, but it will be understood that any 80 type of circuit closing and opening device may be used. Beyond the circuit controlling device 16 the conductor 14 leads to a battery 17, the other side of which is connected to the conductor 15. It will be understood of course that where the circuit controller 16 is sufficiently remote a suitable 85 ground connection may be used.

The armature lever 8 is provided with an armature 18 controlled by an electromagnet 95 19 one side of which is connected by a conductor 20 to the hand or arm 2 while the other side of this magnet is connected by a conductor 21 to the spring finger 3 adjacent to the spring finger 5 of the armature lever 100 4 controlled by the latch lever 8 in turn controlled by the magnet 19. The conductor 21 includes a battery 22 or other suitable source of electric energy.

It will be understood that the lever 4 105 may be duplicated as many times as may be desired about the clock with its finger 5 in the path of the arm 2 under conditions to be described and that the fingers 3 may also be duplicated, there being a finger 3 for each 110 magnet 19 and a lever 4 for each magnet 13. In the drawings two such magnets 13 and

19 with the parts controlled thereby and two watchmen's stations are indicated, but it will be understood that more stations may be installed as desired.

- 5 Each armature lever 4 is connected by a respective conductor 23 to one side of a bell 24 or other signal or indicating device while the other side of this bell is connected by a conductor 25 to the hand 2 and by branch 10 conductors 26 to the side of the magnet or magnets 19 remote from that connected to the respective batteries 22, although of course the batteries 22 may be included in the conductors on either side of the magnets 15 19.

Let it be assumed that the hand 2 is approaching a contact finger 3 and ultimately engages the same, the armature lever 4 being at the time moved against the action of 20 the spring 7 so as to be there held by the head end 9 of the lever 8 which latter is held in the position named by the spring 10 while the circuit of the magnet 13 is open at the controller 16. As soon as the hand 2 engages 25 the contact 3 there is established a circuit from the battery 22 through the conductor 21 to the finger 3, thence by way of the hand 2 to the conductor 25 thence to the conductor 26 and to the magnet 19 and from the latter 30 to the battery 22. The magnet 19 is thereby energized and the armature 18 together with the lever 8 is attracted against the action of the spring 10 to a sufficient extent to carry the head 9 away from engaging relation with 35 the lever 4 and the latter is immediately moved toward the pin 6 by the reaction of the spring 7 which latter has been compressed by the movement of the lever 4 to engaged position with the latch lever 8. The 40 release of the armature lever 4 has caused the movement of the spring finger 5 into the path of the hand 2 and if the movement of the hand 2 be continued said hand will ultimately be brought into electrical contact 45 with the finger 5 and therefore establish a circuit from a battery 27 included in the conductor 25 through the latter to the hand 2, thence by way of the finger 5 to the armature lever 4 and from the latter by the conductor 50 23 to the bell 24 and back to the battery 27 thus causing the bell to give a signal, or if the bell be replaced by some other indicating or signaling device then the operation of such device will be brought about and will 55 cease as soon as the progressive movement of the hand 2 has carried it out of electrical contact with the finger 5. If however before the finger 2 has reached the finger 5 the circuit controller 16 be moved to the closed circuit 60 position then there is established a circuit from the battery 17 by way of the conductor 15 to the magnet 13 and back to the battery through the circuit controller 16 by way of conductor 14. The magnet 13 is thus 65 energized and the armature 12 is attracted

thus moving the armature lever 4 against the action of the spring, compressing the same until the free end of the lever 4 snaps back of the head 9 of the latch lever 8 and the latter moves into the path of the free end of the lever 4 under the action of the spring 10. This causes a movement of the finger 5 out of the path of the hand 2 so that when the latter reaches the position formerly occupied by the finger 5 it will not engage the same 75 and so no signal will be produced. Therefore if the watchman arrives at the proper station at the proper time and closes the circuit at the controller 16 then the finger 5 is moved out of the path of the hand 2 and no 80 signal is given, but if the watchman be negligent or be detained for any reason and does not close the circuit at the proper circuit controller 16 then the hand 2 having first caused a release of the armature lever 4 will on its 85 progressive movement engage the finger 5 and so cause a signal in the manner already described. A finger 3 and a coacting finger 5 may be placed so closely together as to make it incumbent on the watchman to arrive 90 at the proper station and having there arrived to close the circuit within a very short time interval so that if he arrives at the station too early and closes the circuit before the hand 2 has reached the finger 3 95 this closure will be ineffectual and the signal will be produced at the time the circuit at the local station should have been closed. If the watchman arrives too late then the signal will already have been given. The time interval during which the circuit controller 16 may be effectively closed may be made as short as desirable or as long as desirable. The time interval during which the controller 16 may be effectively operated is 100 105 readily adjustable by moving the finger 3 toward or from the corresponding finger 5 and for this reason each finger 3 may be mounted on a plate or support 28 which may be slotted or otherwise formed so that the finger 110 115 may be secured in adjusted position by a suitable clamp screw 29 or in any other manner.

It will be understood that the hand or arm 2 may be properly designated a contact hand 115 or arm whether it be actually included in the circuit or whether it causes the closing of the circuit between two contacts by bridging them or by forcing one against the other.

What is claimed is:—

1. In a watchman's clock, a contact hand or arm, a contact constantly in the path of said hand, an armature lever, a contact finger carried thereby and movable into and out of the path of the hand by said armature lever, an electromagnet for moving the armature lever in a direction to withdraw the contact finger carried thereby from the path of the hand, a charged circuit including the magnet, a circuit controller in said circuit, 120 125 130

- a latch for holding the armature lever with the finger carried thereby in the withdrawn position, an electromagnet controlling the latch, a charged circuit including the hand, 5 the contact constantly in the path thereof and the last named electromagnet, and a charged circuit including an indicating means and also including the armature lever and the hand.
- 10 2. In a watchman's clock, a contact hand or arm, a contact constantly in the path of said hand and adjustable to determine the time of contact with said hand, an armature lever, a contact finger carried thereby and movable into and out of the path of the hand by said armature lever, an electromagnet for moving the armature lever in a direction to withdraw the contact finger carried thereby from the path of the hand, a 15 charged circuit including the magnet, a circuit controller in said circuit, a latch for holding the armature lever with the finger carried thereby in the withdrawn position, an electromagnet controlling the latch, a 20 charged circuit including the hand, the contact constantly in the path thereof, and the last named electromagnet, and a charged circuit including an indicating means and also including the armature lever and the hand.
- 25 3. In a watchman's clock, a contact hand or arm having a progressive movement, a contact terminal movable into and out of the path of said arm and having a normal tendency toward movement into the path of 30 said arm, an electromagnet for withdrawing said contact from the path of the arm, manually controllable means for causing the energization of said magnet, electromagnetic 35 means for locking the contact out of the path of the arm, and means controlled by said hand or arm for causing the energization of the last named electromagnetic means to release the contact to movement 40 into the path of the hand or arm prior to the arrival of said hand or arm at the position of the contact when in the path of said arm.
4. In a watchman's clock, a contact hand or arm having a progressive movement, a contact terminal movable into and out of the path of said arm and having a normal 45 tendency toward movement into the path of said arm, an electromagnet for withdrawing said contact from the path of the arm, manually controllable means for causing the energization of said magnet, electromagnetic 50 means for locking the contact out of the path of the arm, and means controlled by said hand or arm for causing the energization of the last named electromagnetic means to release the contact to movement 55 into the path of the hand or arm prior to the arrival of said hand or arm at the position of the contact when in the path of said arm, and an indicating means and actuating circuit therefor responsive to the engagement of the hand or arm with the contact movable into and out of the path 60 thereof.
5. In testimony that I claim the foregoing as my own, I have hereto affixed my signature in the presence of two witnesses.
